(57) CLAIM

The ornamental design for a container for a deceased person or animal, as shown and described.

DESCRIPTION

FIG. 1 is a perspective view of an ornamental design for the container for a deceased person or animal;

FIG. 2 is a side view of an ornamental design for the container for a deceased person or animal;

FIG. 3 is a top view of an ornamental design for the container for a deceased person or animal; and,

FIG. 4 is a bottom view of an ornamental design for the container for a deceased person or animal.

The broken line showing of the name and dates is for illustrative purposes only and forms no part of the claimed design.
